UNITED STATES PATENT OFFICE.

AXEL W. CARLSON, OF WORCESTER, MASSACHUSETTS, ASSIGNOR TO CARLING TURBINE BLOWER CO., OF WORCESTER, MASSACHUSETTS, A CORPORATION OF MASSACHUSETTS.

FAN-CASING.

1,370,283.

Specification of Letters Patent. Patented Mar. 1, 1921.

Original application filed May 27, 1918, Serial No. 236,810. Divided and this application filed January 31, 1919. Serial No. 274,295.

To all whom it may concern:

Be it known that I, AXEL W. CARLSON, a citizen of the United States, residing at Worcester, in the county of Worcester and 5 State of Massachusetts, have invented a new and useful Fan-Casing, of which the following is a specification.

This invention relates to a casing through which air may be drawn and discharged by 10 a rotary fan, this specification forming a division of my prior application, Serial No. 236,810, filed May 27, 1918.

It is the general object of my invention to improve the design and construction of 15 such fan casings to the end that a quieter and more efficient operation may be obtained.

With this general object in view, my invention relates particularly to the provision of an improved fan casing or air tube which 20 comprises a substantially cylindrical intermediate portion adjacent the fan blades combined with an enlarged or bell-shaped entrance portion and a conical discharge portion, preferably of small outward taper.

25 Further features of my invention relate to arrangements and combinations of parts hereinafter described and more particularly pointed out in the appended claims.

A preferred form of my invention is 30 shown in the drawing in which Figure 1 is a vertical sectional view of my improved casing, and Figs. 2 and 3 are partial sectional views taken along the lines 2—2 and 3—3 in Fig. 1.

Referring to the drawing, I have shown 35 a fan 10 having blades 11 and mounted on a shaft 12 supported by a bearing 13. My invention resides in the fan casing 14 surrounding the fan 10 and suitably supported, 40 as by a frame 15. This casing comprises an enlarged or bell-shaped entrance portion 16 which preferably extends to a point substantially midway between the sides of the fan blades 11. At this point the portion 16 45 merges with a short substantially cylindrical portion 17, extending approximately to the outer edge of the blades 11, where it joins a conical discharge portion 18, preferably of relatively small outward taper. The ends 50 of the fan blades are closely adjacent the casing.

It has been found in practice that this particular form of fan casing possesses important advantages in use, and that a fan surrounded by a casing of this type operates 55 with increased efficiency and reduced noise, both of which results are extremely desirable. The bell shaped entrance permits the air to move easily and quietly along natural flow lines in approaching the fan. The 60 short cylindrical portion prevents leakage around the tip of the blade and enables the fan to exert efficient pressure on the air, and the gradual expansion in the conical discharge portion reduces back pressure, while 65 substantially preventing the formation of eddy currents. This is particularly important when the air is discharged from the fan casing into an air duct or passage, as the air in applicant's fan casing will be moving 70 substantially along the axis of such duct or passage, when it enters the same from applicant's conical discharge portion.

Having thus described my invention, it will be evident that changes and modifications 75 can be made therein by those skilled in the art without departing from the spirit and scope thereof, as set forth in the claims and I do not wish to be otherwise limited to the details herein disclosed, but what I 80 claim is—

1. In a blower having a fan, a fan casing surrounding said fan, said fan casing having an enlarged entrance portion, a substantially cylindrical intermediate portion closely adjacent the blades of said fan, and a conical discharge portion with a relatively small 85 outward taper.

2. In a blower having a fan, a fan casing surrounding said fan and having a bell-shaped entrance portion extending to a point substantially midway of the width of the fan blades and merging with a substantially cylindrical intermediate portion for the remaining width of said blades, said casing 95 having also a conical discharge portion of relatively slight outward taper leading from said cylindrical portion.

In testimony whereof I have hereunto affixed my signature.

AXEL W. CARLSON.
